UNITED STATES PATENT OFFICE.

JOHN J. MAAS, OF ALBANY, NEW YORK, ASSIGNOR TO CHARLES CROISSANT,
OF SAME PLACE.

LEVER-LATCH.

SPECIFICATION forming part of Letters Patent No. 320,485, dated June 23, 1885.

Application filed March 28, 1885. (No model.)

To all whom it may concern:

Be it known that I, JOHN J. MAAS, a citizen of the United States, residing at Albany, in the county of Albany and State of New York, 5 have invented certain new and useful Improvements in Lever-Latches, of which the following is a specification.

My invention relates to improvements in lever-latches, in which the latch, provided with 10 a lever-handle and two mutual reacting pressing-feet and pivoted to the door-jamb, co-operators with an inclined bearing-plate secured to the door and a bearing-plate secured to said jamb.

15 The object of my invention is to provide a bearing-plate having an inclined surface and attached to the door, and a second bearing-plate attached to the jamb, and a latch having reacting-feet and pivoted to the second bearing-plate at a point between said feet, so that when 20 the latch is made to engage with the inclined surface of the first bearing-plate one of the said reacting-feet will have bearing on the second bearing-plate, and thereby cause the jamb 25 to exert a reacting pressure on the door. I attain this object by the mechanism illustrated in the accompanying drawings, in which—

Figure 1 represents a plan view of my improved lever-latch and devices employed there- 30 with secured, respectively, to the door and jamb, as used. Fig. 2 is a view from above of the same. Fig. 3 is an end view of the same viewed from the handle end of the lever-latch. Fig. 4 is an end view viewed from the opposite end 35 of said latch. Fig. 5 is a view of the pivot-bolt.

The same letters of reference refer to like parts throughout the several views.

In the drawings, A represents the door, and 40 B is the jamb of the same, and C is a handle for operating the door to pull the same open.

A bearing plate, a, having its outer side or outer surface made with an incline in an upward and inward direction, is secured to the 45 door by screws s, or their known equivalents. The drawings show this inclined bearing-plate to be made in connection with handle C, and forming substantially the upper foot of the same, though it may be made independent and 50 separate from the handle with the latter set away from the said plate a.

Secured to jamb B, by screws s', or their equivalents, is the reacting bearing-plate D, which is perforated at e' to receive the pivot-bolt of the latch.

E is a handled lever-latch, of which e is the handle. This latch is provided with pivot-hole e', (shown by dotted lines in Fig. 2,) and projecting from its inner side from a point relatively over the inclined bearing-plate a is the 60 pressing-foot e², and at the end portion thereof, which projects back past the pivot-hole e', is the pressing-foot e³. This pressing-foot is at about the same distance from pivot-hole e', as is pressing-foot e², and is relatively over or 65 opposite bearing-plate D. The bearing-face of foot e² is preferably made with an incline corresponding with the inclined surface of plate a, substantially as shown in Fig. 3. The pivot-hole e' of the lever-latch is made slightly 70 tapering, so as to allow the latch to be adapted to rock slightly on its pivot, that its feet may be readily adapted to have proper bearing on plates a and D without wrenching or bending or straining the pivot-bolt.

75 F is the pivot-bolt, which has its portion f working in pivot-hole e' of the latch made of cylindrical form, while its portion f' passing through plate D and the wood of the jamb is made of a square form, so as to hold with said 80 plate and the wood from turning, and thereby prevent the hole in the wood and said plate becoming worn or enlarged. Both ends of this pivot-bolt are provided with screw-threads, one end receiving the screw-threaded nut m and 85 the other the nut n, by which nuts the bolt will be made to tightly draw the latch to plate D and the jamb B, as may be required. A washer, w, between nut n and the lever-latch, prevents the movements of the latter from 90 working the nut tighter on or loosening it on the screw-threaded stem of the bolt.

The contiguous edges of the door and jamb to which my improvements are applied are preferably made with corresponding, but reversed 95 inclines, as shown at g in Fig. 2, so that the inclined surface of the meeting edge of the door will wedge with that of the jamb, when the former is closed against the latter.

By the above-described improvements the 100 latch is provided with a reacting pressing-foot which will react against the opposite pressing-

foot through the respective plates *a* and *D*, and thereby cause the jamb of the door to react on the door to cause the latter to wedge tightly against the former, while at the same time the pivot-bolt *F* will be relieved of all side strain and liability of its bending outward from the door, as heretofore in lever-latches, and will be held from turning in the wood of the jamb or wearing the hole therein.

10 When the lever is turned with its handle end *e* downward in direction of arrow 1, the lever will, with its pressing-foot *e*², act on the incline of plate *a* to crowd the door inward, while at the same time foot *e*³ will act on plate *D* and prevent the pressure from the door from forcing the lever-latch outward and bending the pivot-bolt. When it is desired to open door *A*, the lever-latch will be thrown upward and around in direction of arrow 2, and to a short

15 distance past a vertical position, when its foot *e*³ will strike stop *h* and hold the lever from further movement.

I am aware that lever-latches have been employed with an inclined bearing-plate on the door, and that this feature is old and well known. I therefore do not claim the same as my invention.

Having described my invention, what I claim, and desire to secure by Letters Patent, is—

The combination, with the bearing-plate having inclined surface *a* and attached to the door, of bearing-plate *D*, attached to the jamb, and the latch *E*, having feet *e*² *e*³, and pivoted to said plate *D* between such feet, the latch being adapted to engage the inclined surface of the plate, the foot *e*² being adapted to exert a pressure upon the door, and the foot *e*³ a reacting pressure upon the jamb, substantially as and for the purpose described.

JOHN J. MAAS.
